UNITED STATES PATENT OFFICE.

REGINALD CHARLES DUGAN, OF MIA MIA, VICTORIA, AUSTRALIA.

WIRE-STRAINER.

1,271,294.

Specification of Letters Patent.

Patented July 2, 1918.

Application filed June 26, 1917. Serial No. 176,951.

To all whom it may concern:

Be it known that I, REGINALD CHARLES DUGAN, a subject of the King of Great Britain, residing at Spring Plains, Mia Mia, 5 in the State of Victoria, Commonwealth of Australia, have invented certain new and useful Improvements in an Improved Wire-Strainer, of which the following is a specification, reference being had therein to the 10 accompanying drawings, forming part thereof.

This invention relates to an improved wire strainer and refers more especially to an implement or device for straining or tensioning fencing wires though it will be understood that it is applicable to other purposes in which straining or tensioning a wire is necessary and that it may even be used as a hoist or the like for hauling or moving 20 a load.

The object of this invention is to provide a wire strainer of simple and inexpensive construction by which the operation of straining wires may be effected while maintaining the same in a straight line and without bending or twisting the wires or damaging the same (such as with serrated grippers) while further the jointing of the two wires may be effected without sacrificing 30 any of the advantage gained when releasing the strainer.

With the foregoing object outlined and with other objects in view, which will appear as the description proceeds, my invention 35 consists in the novel features hereinafter described in detail, reference being had to the accompanying drawings in which I have shown two embodiments of the invention, and the said invention is fully disclosed in 40 the following description and claim.

Referring to the drawings—

Figure 1 is a plan of the wire strainer complete;

Fig. 2 is a longitudinal vertical section of 45 the same;

Fig. 3 is an end view of the same;

Fig. 4 is a cross section on the line $a-a$

Fig. 1;

Fig. 5 is a cross section on the line $b-b$ 50 Fig. 1;

Fig. 6 is a longitudinal section of a modified form of sliding piece showing slot covering extensions;

Fig. 7 is a view of the knot formed in the

wire when the straining is completed and 55 the implement removed.

Fig. 8 is a plan of an alternative construction.

In constructing a strainer according to this invention I take a piece of steel tube 60 A about twelve inches in length, having a slot A³ on its top face for the greater portion of its length, which forms the base piece A. This slotted portion of the tube A is divided at about its center by a pinned ferrule or sleeve A' and a similar ferrule or sleeve A² is secured at the rearward end. At the forward end of the slotted portion of the tube is secured a block B having a flat face which forms a seat for the pivoted handle 70 or lever C. At the extreme front end of this block B is provided a hook or nose piece B' upon which the standing wire S is looped, the said hook being longitudinally slotted as at B² for the accommodation of the strained 75 wire P. This hook or nose piece B' is made slightly inclined upward so that the loop of wire may be easily released therefrom when the straining operation is completed. Within the before described slotted portion 80 of the tube A is provided a pair of sliding pieces D and E the forward one of which D has a spring D' bearing against the stop formed by the block B while the rear one E has a spring E' bearing against the stop 85 formed by the pin of the central ferrule A'. The sliding piece D is provided with a gripper which comprises a cam D² (which is preferably under cut) pivoted at D³ and bearing against a shoulder D⁴ which has a slight 90 curved recess D⁵ to afford a secure grip for the wire. Similarly the sliding piece E has a gripper comprising a cam E² pivoted at E³ and bearing against a shoulder E⁴ which 95 also has a slight curved recess E⁵. The disposition of the cam shaped grippers D² and E² upon their pivot points D³ and E³ relative to the shoulders D⁴ and E⁴ respectively is such that the point of the cams are just prevented from passing by the shoulders D⁴ and E⁴ while the shape of the cams coincides with the recesses D⁵ and E⁵ so that a maximum leverage and gripping effect is obtained. These grippers D² and E² are connected to the pivoted lever or handle C 100 upon opposite sides of the pivot point thereof by connecting rods D⁶ and E⁶ respectively so that in operation while one is advancing

90

105

the other is receding. The cams D^2 and E^2 are formed with trigger finger pieces D^7 and E^7 respectively whereby the wire held thereby may be released. The standing wire 5 S is looped over the hook or nose piece B' as shown in Figs 1 and 2. The wire P to be strained is inserted between the gripping cam E^2 and the shoulder E^4 and then between the gripping cam D^2 and the shoulder 10 D^4 . The handle C is then rocked on its central pivot and in so doing causes the sliding pieces E and D to reciprocate within the tubular base piece A , the two traveling always in opposite directions carrying the 15 wire forward on each forward movement and releasing the wire on the backward movement. The handle, through the connecting rods, gives a gripping tension to the cams when the sliding pieces are moved 20 forward and releases the cams when the pieces are moved rearward. In this way on each stroke of the handle a forward movement is imparted to the wire P by the one gripper on one movement and by the 25 other gripper on the other movement, the tension of the springs maintaining the grippers in contact with the wire.

When the end of the strained wire P reaches the forward end of the implement 30 it is inserted into the slot B^2 of the nose piece B' and passed through the loop of the standing wire S . The handle C is then operated until sufficient tension has been placed on the wire P when the two wires 35 P and S are joined together by twisting the wire P on to the wire S as shown in Fig. 7 and the implement may be removed by releasing the grippers D^2 and E^2 on the wire P and unhooking the nose piece B' 40 from the loop of the standing wire S . Thus no advantage gained in the straining operation is in any way lost. Though the implement herein described and illustrated is shown with the grippers sliding within a 45 tubular base piece or guide it will be understood that the said grippers and their supporting sliding pieces may be mounted upon a bar or rod or a pair of bars or rods. In one such alternative construction Fig. 8 the 50 base piece is formed of a rod or bar or tube A having a nose piece or hook (such as B') at one end and a pivoted handle or

lever (such as C) mounted adjacent thereto. Sliding pieces (such as D and E) carrying cam shaped grippers (such as D^2 and E^2) 55 are mounted externally on the said rod or bar or tube A with springs (such as D' and E') wound around the said bar or rod or tube and bearing against suitable stops. The operation of an implement constructed 60 in this manner is precisely the same as that previously described.

From the foregoing, the construction and operation of my improved device will be readily understood and while I have shown and described the preferred embodiments of my invention, it will be understood that various changes and modifications may be made therein without departing from the spirit of the invention or sacrificing any of 70 the advantages of the same.

I claim:

A wire strainer comprising a tubular base piece slotted for a portion of its length and provided at its forward end with a fixed block having parallel furcations spaced apart and extending at right angles to the base piece for securing a wire loop to the same, a handle pivotally connected to said block, sliding pieces located in said tubular base piece and each having an integral jaw provided with a shallow longitudinally curved groove, a movable jaw pivotally connected to each of the sliding pieces and having a curved surface adapted to coöperate 80 with one of the curved grooves for gripping a second wire and moving the same through the space between the furcations, handles integral with the movable jaws, links connecting the handles with the handle, a spring located in the tubular base piece and having one end bearing against the fixed block and its other end engaging one of the sliding pieces, and another spring located in the base piece between the other sliding piece and a fixed member in the base piece. 85

In testimony whereof I have signed my name to this specification in the presence of two subscribing witnesses.

REGINALD CHARLES DUIGAN.
